UNITED STATES PATENT OFFICE

LEON S. BRACH, OF EAST ORANGE, NEW JERSEY

ARTICLE FOR RECEIVING CIGAR OR CIGARETTE STUBS

Application filed December 11, 1929. Serial No. 413,177.

This invention relates to a cigarette snuffer and receiver by which cigarettes may be inserted into sockets formed in a part of the device, whereby a draft of air is cut off from the lighted end and the stubs are then quickly extinguished, after which the holder having the sockets therein, may be opened to deposit the stubs into the receptacle portion of the device.

10 It is one of the objects of my present invention to provide individual holders which are adapted for use in connection with the receiver, or by themselves individually.

Another object of my invention is to provide an article of the character described which is simple and cheap to make, yet one which is artistic in its general appearance.

My present improvement will be readily understood by reference to the annexed drawings, which show certain ways in which the invention may be carried into practice.

Figure 1 illustrates a plan view of a receptacle with one holder mounted thereon.

Figure 2 is a part side elevation, and a sectional view on the line 2—2 of Figure 1, with the receptacle broken away from the front of the holder.

Figure 3 is a view of one type of holder having a base for supporting the holder, which base is adapted to fit on a table or in a receptacle.

Figure 4 shows another method of mounting the holder per se on the table or the like.

Figure 5 is a plan view of the holder showing another detail slightly modified.

Figure 6 is a further modified form of holder.

Figure 7 is a side elevation of Figure 6.

In the drawings, wherein like numbers refer to corresponding parts in the various views, 1 is a receptacle having a rim 2. A holder for the cigarette or cigar stubs is composed of two parts, 3 and 4, the part 3 being composed of a part socket-portion 6 and a handle portion 8, while the part 4 is composed of a part socket-portion 7 and a handle 9. The parts 3 and 4 are pivotally mounted together by a pivot pin 5. A spring 10 acts between the parts of the handles 8 and 9 to normally force them apart and to force the

socket portions 6 and 7 together, thereby keeping the socket 15 normally closed.

As shown in Figure 1, a plurality of holders are adapted to have their pivot pins 5 mounted in the holes 11 around the perimeter of the rim 2.

From the above description, it will be seen that after the socket 15 has become filled with ashes or stubs, and it is desired to drop them into the receptacle 1, which may be of any desired diameter and depth, pressure on the handle portions 8 and 9 will open the socket 15 and drop the contents thereof into the receptacle.

In the form of holder shown in Figure 5, the parts of the holder, 3 and 4, are fastened together by a pivot pin 5 which has a hole 14 therethrough. When this construction is used, pins are used on the rim 2 in place of the holes 11, and it will then be apparent that the holders may be slipped off the pins for the purpose of cleaning and the like. When this form is used, it is preferable to make the bottom of the socket portions flat, as shown in Figure 7, so that the holder may be self-supporting.

In Figure 3, the pivot pin has an extension 12 to which is attached a plate 13 which may be of heavy material or weighted, so as to make the device stable, whether placed on a table or in a receptacle. Otherwise, the holder is similar to the forms previously described.

In Figure 4, the pivot pin 5 has an extension 17 which is fastened to a spring member 16 adapted to be slipped over the edge of the table, such as a card table.

In the forms shown in Figures 6 and 7, the socket parts 6 and 7 of the holder have grooved flanges 19, so that the cigarette may be laid transversely across the top of the holder. A one-piece spring 18 has its ends 20 and 21 anchored intermediate the handle and socket portions and closely adjacent the fulcrum edge where the two parts come together. The spring 18 is so formed that the bottom portion provides a supporting base which will support the holder. Furthermore, the spring is so formed that the bottom part may be slipped over the edge of a

suitable receptacle, thereby supporting the holder on the rim of such receptacle. The spring therefore acts in a double function; that of holding the two parts of the holder together so that the socket 15 is normally closed, and as a supporting means for the holder. It will be clear from Figure 6 that when pressure is applied to the handle portions 8 and 9, the socket portions 6 and 7 are spread apart as the two parts turn about or fulcrum at a point closely adjacent the point where the ends of the springs 20 and 21 are anchored.

It will be apparent that various changes may be made in the details of my invention without departing from the spirit of my invention or the scope of the appended claims.

Having thus described my invention, what I claim is:

1. A device of the class described, comprising a receptacle, a holder mounted on the outer part of the receptacle and extending toward its center, said holder being composed of two parts pivoted together intermediate their ends, the portions which extend toward the center of the receptacle being shaped to form a closed end socket to receive a cigar or cigarette stub, while the other portions are spaced apart to form a handle, and a spring member positioned between said handle portions and normally acting to force them apart to hold the socket closed.

2. A device of the class described, comprising a receptacle, a plurality of pins carried thereby around its outer periphery, a holder adapted to be removably mounted on one of said pins, said holder being composed of two parts pivoted together intermediate their ends, the portions which extend toward the center of the receptacle being shaped to form a closed end socket to receive a cigar or cigarette stub, while the other portions are spaced apart to form a handle, and a spring member positioned between said handle portions and normally acting to force them apart to hold the socket closed.

3. For a device of the class described, a holder composed of two parts pivoted together on a pin intermediate their ends, said parts forming a closed end socket on one side of the pivot to receive a cigar or cigarette stub, and extending in spaced relation on the other side of the pivot, and means normally acting between said spaced portions to force them apart and the socket portions together, said pin being extended and having a support member attached thereto on the lower side of the holder.

4. For a device of the class described, a holder composed of two parts pivoted together intermediate their ends, said parts forming a closed end socket on one side of the pivot to receive a cigar or cigarette stub, and extending on the other side of the pivot to form a handle, and means normally acting on

the handle portions to hold the socket portions closed together.

5. For a device of the class described, a holder composed of two parts pivoted together on a pin intermediate their ends, said parts forming a closed end socket on one side of the pivot to receive a cigar or cigarette stub, and extending in spaced relation on the other side of the pivot, and means normally acting between said spaced portions to force them apart and the socket portions together, said pin extending on the lower side of the holder and having a flat plate of considerable area attached thereto.

6. For a device of the class described, a holder composed of two parts pivoted together by a hollow rivet intermediate their ends, said parts forming a socket on one side of the pivot to receive a cigar or cigarette stub and extending on the other side of the pivot to form a handle, and means normally acting on the handle portions to hold the socket portions closed together.

7. For a device of the class described, a holder having two parts forming a socket and handle, and a spring having its ends anchored, one in each of said holder parts, intermediate the socket and handle portions, said spring acting to hold the two holder parts together, as well as to permit the socket portions to be pivotally moved apart, and also for supporting the entire holder on a support.

8. For a device of the class described, a holder having two parts forming a socket and handle, and a one-piece spring having its ends anchored, one in each of said holder parts, said spring being formed so as to act to hold the said holder parts in closed position, as well as to allow the socket portions to be separated by force applied to the handle portions and also to act as a support for the holder.

9. For a device of the class described, a holder having two parts forming a socket and handle, said parts being fulcrumed at the juncture of the socket and handle portions, and a spring having ends anchored to said parts closely adjacent the fulcrum point of said parts, said spring being formed so as to act to hold the said holder parts in closed position, as well as to allow the socket portions to be separated by turning about said fulcrum by force applied to the handle portions, and also to act as a support for the holder.

10. For a device of the class described, a holder having two parts forming a socket and handle, and a spring having at least one end anchored in one of said holder parts, said spring acting as a support for the holder.

In testimony whereof, I affix my signature.

LEON S. BRACH.
